UNITED STATES PATENT OFFICE

97,301

DESIGN FOR A SHOE OR SIMILAR ARTICLE

Samuel Morgenstern, New York, N. Y.

Application September 10, 1935, Serial No. 58,499

Term of patent 3½ years

To all whom it may concern:

Be it known that I, Samuel Morgenstern, a citizen of the United States, residing in New York city, in the county of New York, in the State of New York, have invented a new, original, and ornamental Design for a Shoe or Similar Article, of which the following is a specification, reference being had to the accompanying drawing, forming part thereof.

I claim:

The ornamental design for a shoe or similar article, substantially as shown.

SAMUEL MORGENSTERN.
